UNITED STATES PATENT OFFICE.

SAM ALLEN, OF OKMULGEE, OKLAHOMA.

CONCRETE-BLOCK-MAKING MACHINERY.

975,104.

Specification of Letters Patent. Patented Nov. 8, 1910.

Application filed September 11, 1909. Serial No. 517,819.

To all whom it may concern:

Be it known that I, SAM ALLEN, a citizen of the United States, residing at Okmulgee, Okmulgee county, State of Oklahoma, have 5 invented certain new and useful Improvements in Concrete-Block-Making Machinery, of which the following is a specification.

This invention has reference to concrete block molding machines and is designed to 10 construct a machine wherein a rotary table is used, said rotary table being automatically stopped at predetermined intervals while the concrete in one of the molds is tamped.

It also contemplates the provision of 15 means whereby the core of the mold adjacent to the one being tamped may be removed while the former operation is in progress.

A further object of this invention is to 20 supply a means of readily removing the cores and of locking the removing means.

With the above and other objects in view, this invention consists of the construction, combination and arrangement of parts all 25 as hereinafter more fully described, claimed and illustrated in the accompanying drawings, wherein:

Figure 1 is a side elevation of a machine constructed in accordance with the present invention partly in section; Fig. 2 is a front 30 elevation thereof, a portion of the same being broken away.

Reference being had to the drawings I indicates a plurality of I-beams embedded in concrete supporting the base frame 19 of 35 the machine. A vertical upright frame C is carried approximately centrally at one extremity of the base frame and supplies a means of supporting the drive gears and a portion of the vertical shafts. At the upper extremity of the vertical frame C is the horizontal support B, said support being approximately U-shaped and adapted to form a housing for the upper ends of the vertical shaft. The outer portion of this horizontal 40 shaft B is supported by the brace 4 interposed between the terminal of the bar B and the vertical frame C. To the rear of the frame C extends the vertical bar N provided with a pillar block at its upper extremity in which 45 rotates the shaft L operating between the vertical brace and the frame C, said shaft carrying the large and small gears F and G. A shaft E is mounted in the frame C above the shaft L and is provided at one extremity 50 with the large gear D adapted to mesh with

the small gear G carried by the shaft L, and at the other extremity with the disk 7. The entire train of gears is driven by the shaft M operated by a belt over the pulley J and operating a small gear O meshing with the 60 large gear F of the shaft L.

A vertical shaft H is mounted at its lower extremity in the step bearing and box 18 and 20. The upper extremity of the shaft is secured in the slidable mounting 1 in such 65 a manner that the shafts may be swung outwardly about its lower bearing as an axis. The shaft H carries the rotatable table 12 upon which are secured the molds 11, said molds being rigidly carried by said table. 70

In order to supply a means whereby the shaft H may be tilted outwardly a rod 25 operates vertically in one side of the frame C and is reciprocated therein by the lever 27. To a collar mounted on this rod are pivotally 75 connected a pair of auxiliary levers, one of said auxiliary levers being rigidly connected to the rear terminal of the frame B while the remaining lever is pivotally connected to the reciprocating rod 26, said rod being retained 80 on the frame B by a plurality of collars. The outer terminal of the rod 26 is curved upwardly and operates against the bearing 1 of the upper terminal of the bar B. A spring operates between the bar B and the 85 collar on the rod 25 and normally retains the auxiliary levers from said bar, but upon lowering the rod against the pressure of said spring, the lever 26 is forced outwardly by the auxiliary lever secured thereto and as a 90 result tilts the shaft outwardly about the lower mounting as an axis.

The table 12 is provided about the periphery thereof with a plurality of lugs 13, said lugs adapted to coöperate with a projecting 95 lever or bar operated by the lever 28 carried by the frame C. Each of these lugs are located centrally with respect to a mold, and consequently, necessarily stops the table 100 from rotation in such a manner that the mold adjacent thereto is located directly under the tamping mechanism.

The tamping mechanism comprises the shaft 8 operating in the brackets 3 and 9 secured to the frame C. A cross head 5 is 105 rigidly secured adjacent the upper extremity of the shaft and between the brackets 3 and 9, to which is connected the pitman 6, the opposite end of said pitman being connected to the disk 7. From this construction it will 110

readily be seen that upon rotating the train of gears heretofore described the shaft 8 will be reciprocated vertically and the tamp 10 be driven into the mold.

5 The base of the mold is provided with an opening which extends entirely through the table into which the core 31 is injected. A plate 32 surrounds the core and is removable from the mold in such a manner that the 10 same carries the block molded therein with it.

The core is attached to a rod 17, the lower terminal of which is bent outwardly, said rod operating in the frame 14 and adapted to withdraw the core from the mold upon the 15 lower reciprocation thereof.

A bar 16 is secured to the rod and has interposed between each extremity thereof and the base of the table, a spring 15 which is adapted to project the core within the mold.

20 In order to remove the core from the mold, a lever 22 is pivoted to one of the I-beams and is curved outwardly at its outer extremity in such a manner that when the contents of one mold are being tamped the terminal of said lever coöperates with the outwardly bent portion of the rod 17 of the next adjacent core. This lever is provided with a treadle 21, and by exerting power on said treadle, the rod 17 is forced downwardly and 25 against the pressure of the spring 15 and withdraws the core from the mold, allowing the block formed in the mold to be removed. An auxiliary lever 24 is secured adjacent to the base of the table and is connected to the lever 22 by a spring, said lever being adapted 30 to aid in removing the core.

A lever 29 is pivoted to the frame and is adapted to coöperate with the levers 22 and 40 24 in such a manner that said levers are locked until the next mold is in position for the core to be removed when the pin 30 carried by the table comes in contact with the upper terminal of the lever 29 and releases the levers 22 and 24 allowing the same to 45 operate. The lever 29 is operated by a spring interposed between the same and the vertical frame C.

The operation is as follows: Assuming that the contents of the mold 11 located under the 50 tamp 10 have been completely tamped, the lever 27 is operated causing the shaft H to swing outwardly as heretofore described and release the lugs 13 which will permit the table to rotate until the next lug comes in 55 contact with the projection operated by the lever 28. When this occurs, the finished mold is located adjacent to the terminals of the levers 22 and 24 when the same are released by the pin 30. Thus, by applying 60 foot power the core is withdrawn from the mold and the finished block may be readily removed. When the next mold is released as heretofore described, the springs will return the core to the mold and new concrete 65 may be placed therein previous to tamping.

Having thus fully described my invention, what is claimed as new is:

1. In combination, a base frame, a vertical frame secured to said base frame, a horizontal frame carried at the upper extremity 70 of said vertical frame, a vertical shaft interposed between said horizontal bar and said base frame, and means whereby the upper extremity of said vertical shaft is slidably mounted on said horizontal bar. 75

2. In combination, a base frame, a vertical frame secured to said base frame, a horizontal frame carried at the upper extremity of said vertical frame, a vertical shaft interposed between said horizontal bar and said base frame, a slidable mounting at the upper extremity of said shaft, and means whereby said slidable mounting may be reciprocated. 80

3. In combination, a base frame, a vertical frame secured to said base frame, a horizontal frame carried at the upper extremity of said vertical frame, a vertical shaft interposed between said horizontal bar and said base frame, a slidable mounting at the 90 upper extremity of said shaft, a table carried by said shaft, a plurality of molds carried by said table, and cores projecting through said table into said mold. 85

4. In combination, a base frame, a vertical frame secured to said base frame, a horizontal frame carried at the upper extremity of said vertical frame, a vertical shaft interposed between said horizontal bar and said base frame, a slidable mounting at 100 the upper extremity of said shaft, a table carried by said shaft, a plurality of molds carried by said table, a plurality of cores projecting through said table and into said mold, and means whereby said cores may 105 be removed.

5. In combination, a base frame, a vertical frame secured to said base frame, a horizontal frame carried at the upper extremity of said vertical frame, a vertical 110 shaft interposed between said horizontal bar and said base frame, a slidable mounting at the upper extremity of said shaft, a table carried by said shaft, a plurality of molds carried by said table, a plurality of cores 115 projecting through said table and into said mold, and means whereby said cores may be removed during the tamping of the succeeding mold.

6. In a concrete block forming machine, 120 a frame, a rotatable table mounted on said frame, a projection carried by said frame, a plurality of studs formed on the edge of said table adapted to engage said projection at predetermined intervals, and means 125 whereby said studs and projection may be disengaged by swinging the axis of the table.

7. In a machine of the class described, the combination with a frame, of a rotatable 130

table carried thereby, a plurality of molds carried by said table, a frame carried under each of said molds, a spring pressed core adapted to reciprocate in said frame, and normally rest in said molds, and means whereby each core may be removed from said molds against the pressure of the spring and be retained in this position during predetermined intervals.

10 8. In a machine of the class described, the combination with a rotatable table, of a plurality of molds carried thereby, a frame carried under each of said molds, a core adapted to reciprocate in each of said frames and be projected by a spring into the mold with which it coöperates, said core being provided with a shank, means whereby said shank may be engaged at predetermined intervals and the core removed automatically from said mold and retained in this position previous to the removal of the block and during the tamping of the plastic in the preceding mold.

9. In a machine of the class described, the combination with a frame, a rotatable table carried thereby, a plurality of molds carried by said table, a frame carried under each of

said molds, a core carried by said frame adapted to be projected into said molds, a shank formed on each core, a bar operating on said shank, and springs operating between said bar and table adapted to project said core into the mold.

10. In a machine of the class described, the combination with a frame, a rotatable table carried thereby, a plurality of molds carried by said table, a frame carried under each of said molds, a core carried by said frame adapted to be projected into said molds, a shank formed on each core, a bar operating on said shank, springs operating between said bar and table adapted to project said core into the mold, and a lug formed at the lower terminal of said shank adapted to be engaged at predetermined intervals and remove said core from the molds.

In testimony whereof I have signed my name to this specification in the presence of two subscribing witnesses.

SAM ALLEN.
